SOCK DISPLAY HANGER

Allen I. Field, 147 Valley Stream Road, Larchmont, N.Y.

Filed Aug. 23, 1961, Ser. No. 66,470

Term of patent 14 years

(Cl. D80—8)

FIG. 1

FIG. 1 is a side elevational view of a sock display hanger, showing my design;

FIG. 2 is a top plan view of the same; and

FIG. 3 is an end elevational view thereof taken from the left of FIG. 1.

I claim:

The ornamental design for a sock display hanger, substantially as shown.
